CONTACT REFRIGERATION UNIT FOR CHILLING DRINKING VESSELS

Richard F. Starrett, P.O. Box 838,
Tiburon, Calif. 94920

Filed July 27, 1973, Ser. No. 383,140

Term of patent 14 years

Int. Cl. D15—07

U.S. Cl. D67—4

FIG. 1 is a perspective view of a contact refrigeration unit for chilling drinking vessels, incorporating my invention.

FIG. 2 is a view in side elevation thereof.

FIG. 3 is a view in end elevation thereof.

FIG. 4 is a view in top plan thereof, and

FIG. 5 is a view in bottom plan thereof.

I claim:

The ornamental design for a contact refrigeration unit for chilling drinking vessels, substantially as shown.
